WILLIAM GRAMBART, OF BROOKLYN, NEW YORK.

MECHANICAL DIAPHRAGM-SIGNAL.

1,174,567.

Specification of Letters Patent. Patented Mar. 7, 1916.

Application filed November 13, 1914. Serial No. 871,850.

To all whom it may concern:

Be it known that I, WILLIAM GRAMBART, a citizen of the United States, and a resident of the borough of Brooklyn, in the county of Kings and State of New York, have invented certain new and useful Improvements in Mechanical Diaphragm-Signals, of which the following is a specification.

This invention is an improvement in signals, wherein a diaphragm is vibrated by mechanical means to produce the sound, and the object is to provide an exceedingly simple, durable, low cost and at the same time effective construction.

The invention comprises certain novel and important features of construction and relation, which will hereinafter appear and be more particularly set forth in the appended claims.

In the accompanying drawings: Figure 1 is a vertical longitudinal section through a horn signal embodying the invention, the projector being broken away and parts within the back case being shown in elevation; Fig. 2 is a rear elevation, with the back case removed and the operating handle in cross-section; Fig. 3 is a plan view, partly in section and partly broken away, showing the operating mechanism and its tiltable supporting frame; and Fig. 4 is a detail vertical section on an enlarged scale showing the fulcrum joint and indicating the movability of the tilting frame member by dotted lines.

The fixed framework of the signal consists primarily in this instance of a back diaphragm clamp ring 2, which with a front case member 3 holds the marginal portion of a diaphragm 4, gaskets 5 being interposed and the parts being secured together by screws 6, as is usual. From an opening in the front case there extends a suitable horn or projector 7. The diaphragm is provided centrally or in its interior portion with an anvil 8, which is acted upon by a toothed wheel 9 to displace the diaphragm in the customary manner. The invention is particularly concerned with the mounting and adjustment of this rotary actuator and its operating mechanism.

A frame 10 is provided behind the diaphragm, and in this instance comprises a forward base portion 11, bridging and secured to the back diaphragm clamp ring 2, and rearwardly-extending laterally-spaced side portions 12 formed integral or otherwise united with the front portion. By and

between these side portions, the actuator 9 and its driving gearing are supported, the periphery of the ratchet-like actuator operating upon the anvil 8 through an opening 13 in the frame front portion. In the preferred embodiment the actuator is journaled on a sleeve or hollow shaft 14, which is indicated by dotted lines in Fig. 3, and bears at opposite ends a pinion 15 and a ratchet 16, the ratchet being coupled with the actuator for one-way movement by means of a pawl 17 and a spring 18 mounted on a fly wheel element 19 united with the actuator. The primary driving gear is shown as consisting of a gear segment 20, meshing with the pinion 15 and united with a rearwardly projecting handle 21. This lever carries an operating knob 50, which is disposed in rear of the back case in position to be depressed by a downward movement of the hand. The sleeve or hollow shaft 14 is journaled on a fixed shaft 22 connecting the side portions 12 of the frame, while the segment 20 and handle 21 are pivotally mounted by being secured to a shaft 23 rotatable in the frame. A spring 24, coiled about the latter shaft and secured at one end thereto and at the opposite end bearing against a cross-piece 25, serves to return the handle to normal position after being depressed.

It will be observed that the pinion 15 and ratchet 16 on the sleeve 14 at opposite sides of the diaphragm actuator afford lateral support to this wheel and space the same from the side plates 12. Furthermore, the construction facilitates assembling since the sleeve with the actuator, pinion, ratchet and pawl constitute a unit, which is placed between the said side plates and then held in place by the fixed shaft 22. The parts in rear of the diaphragm are inclosed by a back case 26 having a vertical slot 27 in its rear wall, to permit the passage and operation of the handle 21, and an enlarged forward portion 28 terminating in a flange 29 secured to the diaphragm clamp ring 2.

The adjustment between the diaphragm and its actuating mechanism to secure the proper tone is effected by tilting of the frame 10 carrying the actuator 9 and the drive mechanism, the frame being fulcrumed on a fixed part, namely the clamp ring 2, at one side of the diaphragm center and provided with an adjuster 30 at the opposite side of said center, the actuator being supported in relation intermediate the fulcrum

and adjuster, the arrangement thus being of a movement-reducing character, enabling an especially fine adjustment to be secured. The fulcrum joint between the tiltable frame and the diaphragm clamp is preferably located at the top and the adjuster 30 at the bottom, where it is accessible without removing the case 26 by virtue of an opening 31 formed in the flaring portion 28 and enabling the adjuster to project outside, as shown in Fig. 1. The fulcrum joint, shown more particularly in Fig. 4, comprises a curved lug 32 on the frame and a portion 33 on the diaphragm clamp, the two being united by a screw fastening 34 substantially perpendicular to the diaphragm and the member 32 of the joint having its convex bearing face presented to the face of the member 33 so as to enable the frame to rock when acted upon by the adjuster. The screw 34 passes loosely through an opening 35 in the frame lug 32 to engage a threaded opening in the part 33, and the under surface 36 of its head is rounded or convexed for engagement with the concave side of the lug 32. The adjuster comprises a stud bolt 37, fixed to and projecting rearward from the lower portion of the back diaphragm clamp and passing loosely through an aperture in an offset lug 38 on the bottom of the frame portion 11, and in addition thereto nuts 39 and 40 on the bolt at opposite sides of the said lug, enabling the frame to be moved in one direction or the other and held fixed at the desired adjustment.

A convenient manner of sounding the signal is for the operator to grasp the back case with the thumb and fingers and with the purchase thus obtained to press down with the ball of the hand upon the knob 50. This swings the lever 21 downward and moves the gear segment 20 upward, thereby rotating the pinion 15 in the direction which produces operative engagement of the pawl and ratchet, so as to revolve the actuator 9 at high speed in contact with the diaphragm wear piece. By this construction a powerful impulse can be imparted very easily to the operating mechanism, producing a succession of diaphragm impacts of requisite number and frequency with only a single gear multiplication. When the pressure is removed from the operating knob, the spring 24 restores the gear segment and handle to normal position, but in this movement the ratchet 16 rides idly beneath the pawl 17 on the actuator, which is consequently not driven in this direction.

What is claimed as new is:

60 1. In a mechanically actuated diaphragm signal, the combination with a fixed frame supporting and clamping the diaphragm and carrying a horn and a back case at opposite sides thereof, of a rotary actuator and operating means within said back case,

and a tiltable frame carrying the actuator and operating means, said tiltable frame having a portion at one side of the actuator fulcrumed on the rear face of said fixed frame and connected thereto by a pin substantially perpendicular to the diaphragm, and an adjuster for the tiltable frame at the opposite side of the actuator. 70

2. In a mechanically actuated diaphragm signal, the combination with a fixed frame supporting and clamping the diaphragm and carrying a horn and a back case at opposite sides thereof, of a rotary actuator and operating means within said back case, and a tiltable frame carrying the actuator and operating means, said tiltable frame comprising an open front portion through which the periphery of the actuator projects, the said front portion lying adjacent the diaphragm and being fulcrumed at one side of the center on the rear face of the fixed frame by means of a pin substantially perpendicular to the diaphragm, and having an adjusting device at the opposite side of the center, said frame comprising also parallel side portions projecting rearward from the forward portion, the actuator and operating means being supported by and between said side portions. 85

3. In a signal, a diaphragm, a fixed frame, a frame tiltable toward and from the diaphragm and carrying means for actuating the same, said tiltable frame having a fulcruming-face bearing on said fixed frame formed with a convex rocking face, and a fastening substantially perpendicular to the diaphragm uniting the tiltable and fixed frames at said bearing. 90

4. In a signal, the combination of a diaphragm, a fixed part behind the diaphragm, 105 a frame having a curved apertured bearing portion with its convex face opposed to said fixed part, a screw passing loosely through the aperture in said bearing portion into said fixed part and having a head with a convex under portion engaging the concave side of the bearing portion, an adjusting device connected with the frame, and means on the frame for actuating the diaphragm. 110

5. In a signal, a diaphragm, a fixed frame lying adjacent thereto, a tiltable frame fulcrumed for movement on the fixed frame toward and from the diaphragm, mechanism mounted on said tiltable frame for actuating the diaphragm, a back-case inclosing said tiltable frame and mechanism and having a flaring base by which it is united to the fixed frame, said flaring base having a recess therein, and an adjuster for said tiltable frame projecting through said recess in the flaring base of the back case. 115

6. A mechanically actuated diaphragm horn, comprising a diaphragm and diaphragm case, a projector extending forward therefrom and a rearwardly extending back 120

case, in combination with mechanism in said back case comprising a rotary toothed actuator, and multiplying gearing for driving said actuator including a large gear segment and a one-way acting connection between the same and the actuator, an operating lever united with said segment and extending rearward from the back case, and a knob on said lever in rear of said case close to the rear wall of and substantially at the same height as the top of the case; whereby the lever may be operated by downward pressure applied by the ball of the hand, the fingers resting on the case.

15 7. A mechanically actuated diaphragm horn, comprising a diaphragm and diaphragm case, a projector extending forward therefrom and a rearwardly extending back case, in combination with mechanism in said back case comprising a rotary toothed actuator, and multiplying gearing for driving said actuator including a large gear segment and a one-half way acting connection between the same and the actuator, an operating lever united with said segment and extending rearward from the back case, and a knob on said lever close to the

rear wall of the case between the projections of the side lines thereof and substantially at the same height as the top of the case, 30 whereby the lever may be operated by downward pressure applied by the ball of the hand, the fingers resting on the case.

8. In a mechanically actuated diaphragm signal, the combination with a plane fixed 35 frame supporting and clamping the diaphragm and carrying a horn and a back case at opposite sides thereof, of a tiltable frame mounted on the fixed frame within the back case, said tiltable frame being fulcrumed at one end directly on the rear face of the fixed frame and having an adjustable connection with the fixed frame at its opposite end, a rotary actuator journaled in the frame intermediate the fulcrum and adjustable connection, and means for actuating said actuator, a shaft on the tiltable frame in rear of said actuator, a driver on said shaft geared to the actuator, and a handle for operating said driver.
